(57) **CLAIM**

I claim the ornamental design for an adjustable telescoping wheelchair handle, as shown and described.

DESCRIPTION

FIG. 1 is a reduced rear, top, and right side elevation perspective, view of the adjustable telescoping wheelchair handle fully extended, in place mounted on a wheelchair; FIG. 2 is a left side elevation perspective view of the adjustable telescoping wheelchair handle fully extended; FIG. 3 is a rear view of the adjustable telescoping wheelchair handle fully extended; FIG. 4 is a right side elevation view of the adjustable telescoping wheelchair handle fully extended; FIG. 5 is a front view of the adjustable telescoping wheelchair handle fully extended; FIG. 6 is a top plan view of the adjustable telescoping wheelchair handle fully extended; FIG. 7 is a bottom plan view of the adjustable telescoping wheelchair handle fully extended; FIG. 8 is a left side elevation view of the adjustable telescoping wheelchair handle fully retracted; FIG. 9 is a rear view of the adjustable telescoping wheelchair handle fully retracted; FIG. 10 is a top plan view of the adjustable telescoping wheelchair handle fully retracted; FIG. 11 is a right side elevation view of the adjustable telescoping wheelchair handle fully retracted; FIG. 12 is a bottom plan view of the adjustable telescoping wheelchair handle fully retracted; FIG. 13 is a front view of the adjustable telescoping wheelchair handle fully retracted; and, FIG. 14 is an enlarged exploded partial bottom, rear perspective view of the adjustable telescoping wheelchair handle base mount showing assembly of the base mount parts.

The broken lines shown in FIG. 1 illustrate environmental structure for the wheelchair that the adjustable telescoping wheelchair handle is mounted to, and forms no part of the claimed design.

1 Claim, 3 Drawing Sheets
